UNITED STATES PATENT OFFICE.

WILLIAM J. FRISBIE, OF CHICAGO, ILLINOIS, ASSIGNOR TO JUSTRITE MANUFACTURING COMPANY, OF CHICAGO, ILLINOIS, A CORPORATION OF ILLINOIS.

OIL-CUP.

1,389,640.

Specification of Letters Patent. Patented Sept. 6, 1921.

Application filed October 6, 1920. Serial No. 415,108.

To all whom it may concern:

Be it known that I, WILLIAM J. FRISBIE, a citizen of the United States, and a resident of Chicago, in the county of Cook, State of Illinois, have invented certain new and useful Improvements in Oil-Cups, of which the following is a specification.

My invention relates to oil cups, particularly to that class of cup comprising a nipple member permanently connected with the surfaces to be lubricated, and an oil reservoir or cup member having detachable connection with the nipple member. In structures of this kind the oil container of cup member may shake loose and become lost during travel of the vehicle unless efficient provision is made to avoid it. The main object of my invention is to provide efficient means whereby the reservoir or cup member may be readily applied to or detached from the nipple member together with improved means for preventing inadvertent or self-separation of the cup member from the nipple member.

On the accompanying drawing, I have shown a construction in which my improved mechanism is embodied. On this drawing—

Figure 1 is a side elevational view of the oiling structure,

Fig. 2 is an enlarged bottom view of the cup member,

Fig. 3 is a side elevational view of the nipple member.

Fig. 4 is an enlarged plan view of the nipple member, and

Fig. 5 is an enlarged vertical diametral sectional view of the entire structure.

The nipple structure N, is preferably formed integral of sheet metal and comprises the upper cylindrical section 10, whose lower part 11 is conical, the intermediate polygonal section 12, and the lower threaded section 13 for engaging in the threaded entrance of a passageway leading to surfaces to be lubricated. The upper cylindrical section 10 is externally threaded as clearly shown in Figs. 3 and 5. The cup member is constructed of sheet metal and comprises the cylindrical body part 14 having the dome shaped top 15. The cup is closed at its lower end by the closure member designated as a whole 16, and comprising the top 17 extending diametrically across the cup, and the downwardly extending cylindrical flange 18 which is threaded on its

interior to fit the threads on the upper section 10 of the nipple member. In the arrangement shown, the wall 17 has at its center the opening 19 surrounded by the upstanding flange 20 in which opening and flange is seated at its lower end the tube 21 which extends upwardly well to the top of the cup. The cup closure member and tube are thus rigidly connected together. The cup is strengthened and finished off at its lower end by the flange 22 extending laterally under the cup edge from the lower end of the side wall 18 of the closure member as clearly shown in Fig. 5.

Securely seated within the upper section 10 of the nipple member is the inverted cup member 23. The horizontal wall of this member has the central opening 24 surrounded by the flange 25 which receives and supports the feed spindle 26, this spindle receiving the tube 21 of the cup member when the cup member is screwed on to the spindle member. The spindle supporting base 23 has the annular depression or pocket 27 for receiving the sealing washer 28, the wall 17 of the oil cup closure member having a similar pocket 29 for receiving the upper section of the washer when the cup and nipple structures are secured together. When the cup structure is to be used, the nipple member is secured to the support leading to the surfaces to be lubricated. The cup member is then inverted and oil filled therein through the tube 21, vent openings 30 being provided in said tube near the bottom thereof for the escape of air while the cup is being filled. The cup is then righted and applied with its tube receiving the spindle 26, the cup being then turned to bring its threads into engagement with those of the nipple structure until the cup and nipple members are tightly drawn together into clamping engagement with the washer 28, there being then no chance for direct flow of oil from the cup into the nipple member. When the vehicle is traveling the cup structure is jolted and bodily moved with the vehicle so that oil therein is splashed up and into the top of the spindle 26. The dome shaped top 15 assists in deflecting thrown up oil into the discharge spindle and the upper end of the tube 21 is also cut out to leave passageways 31 for the oil to the discharge spindle. The spindle is of such diameter relative to the tube 21 that

the tube will readily receive the spindle and allow the cup member to be readily applied to the nipple member.

During heavy travel of a vehicle, the oil cups are violently agitated and jerked and jolted and even with the threaded engagement between the cup member and the nipple member as shown on the drawing, the cup member is apt to work loose from the nipple member. The important object of my invention is to prevent such inadvertent separation or loosening of the cup member. The mechanism of my invention is clearly shown in Fig. 5. Within the chamber formed by the upper section of the nipple member and the spindle supporting member 23 is arranged a coil or spiral spring 32 which seats on the floor of the chamber and whose upper end 33 is deflected vertically and extends through the opening 34 provided in the upper wall of the spindle supporting member 23. The wall 17 of the closure member 16 for the oil cup is deflected to provide a circular row of depressions 35 for receiving the end 33 of the spring when the cup member is threaded into place on the nipple member. When the cup member reaches the bottom of its travel during application thereof to the nipple member, the pockets 35 will receive the spring end 33 and the end will be forced downwardly and the spring compressed. The resistance offered by the engagement of the spring pressed end in the pockets is sufficient to lock the oil cup and nipple member together and prevent inadvertent separation thereof, while at the same time, the cup can readily be turned to be applied to or removed from the nipple member. All the parts of the cup being made from sheet metal or from stock material, the structure is very simple and light and possesses great strength.

Having described my invention, I claim as follows:

- 45 1. In an oiling device, the combination of a nipple member adapted to be secured to a support, an oil cup member having a closed bottom, an internally threaded flange on the lower end of said cup member having threaded engagement with said nipple member, said cup member having an oil outlet for communicating with the nipple member, depressions in the bottom wall of said cup member, and a spring pressed finger on said nipple member for frictionally engaging with said depressions when the cup member is applied to the nipple member whereby separation of the members is prevented.
- 55 2. In an oiling device, the combination of a nipple member having external threads at its upper end, a cup member adapted at its lower end for threaded engagement with said nipple threads, a bottom wall for said cup member, an oil outlet through said wall

for communicating with the nipple member, the upper wall of said nipple member having an opening, a spring housed within said nipple member and having its end projecting upwardly through said opening, the bottom wall of said oil member having detent depressions for coöperation with said spring end to lock the cup member to the nipple member after threaded engagement of such members.

3. In an oiling device, the combination of a nipple member having a top wall and having threads, a cup member adapted at its lower end for engagement with said threads to be thereby held on the nipple member, said oil cup being closed at its lower end by a wall and said wall and the upper wall of said nipple member having oil passageways for the flow of oil from the cup to the nipple, the upper wall of the nipple member having an opening, a coil spring housed within said nipple member and having its end projected through said opening, and detent depressions in the bottom wall of said cup member for coöperation with said spring end to lock the cup member against inadvertent separation from said nipple member.

4. In an oiling device, the combination of a nipple member adapted for being secured on a support, the upper end of said nipple member being cylindrical and having external threads, a cylindrical cup member having internal threads at its lower end for engaging with the nipple threads, a wall above the cup threads closing the lower end of said cup, means affording oil flow passageway between the cup and nipple members when said members are screwed together, said cup wall having detent formation on its under side, and a helical spring held within the nipple member with one end projected in the path of said detent formation to coöperate therewith to lock the cup member against inadvertent separation from the nipple member.

5. In an oiling device, the combination of a nipple member adapted to be secured on a support, a cup member having threaded connection with said nipple member, a bottom wall for said cup member, a removable top wall for said nipple member, said walls having registering openings for the flow of oil from the cup member to the nipple member, a spring housed within said nipple member and having its end projecting upwardly to the nipple top wall, the bottom wall of said cup member having detent formation for coöperation with said spring end to lock the cup member to the nipple member after threaded engagement of such members.

In witness whereof, I hereunto subscribe my name this 1st day of October, A. D., 1920.

WILLIAM J. FRISBIE.
